Primary Examiner — Cynthia Ramirez*Assistant Examiner* — Gino Colan(74) *Attorney, Agent, or Firm* — Brinks Gilson & Lione; Ryan L. Marshall(57) **CLAIM**

The ornamental design for a bagging machine cabin, as shown and described.

DESCRIPTION

FIG. 1 is a perspective view of an embodiment of a bagging machine cabin according to the present invention in a retracted position.

FIG. 2 is a perspective view thereof in an extended position.

FIG. 3 is a right side elevation view thereof;

FIG. 4 is a bottom view thereof;

FIG. 5 is a front elevation view thereof; and,

FIG. 6 is a rear elevation view thereof.

The broken lines in the drawings are included for the purpose of illustrating environmental structure only and form no part of the claimed design.

1 Claim, 5 Drawing Sheets---
